INKING ROLLERS

Andrew J. Alessi, Jr., Colonia, N. J., assignor to Adolph Gottscho, Inc., Hillside, N. J., a corporation of New York

Application October 16, 1952, Serial No. 315,159

8 Claims. (Cl. 101—367)

The present invention relates generally to inking rollers and is particularly directed to an inking roller containing an ink supply and rotating about a vertical axis.

Inking rollers containing the ink supply, that is, fountain rollers, have been heretofore provided for applying ink to type or marking elements carried on the periphery of a marking cylinder rotating about a vertical axis in a device marking the sides of articles. However, such inking rollers are deficient in failing to provide uniform application of ink in the axial direction, and this defect is particularly marked as the supply of ink within the roller is progressively diminished.

Accordingly, an object of the present invention is to provide a fountain roller of the described character which is capable of applying ink uniformly to type or marking elements carried on the periphery of a marking cylinder rotating about a vertical axis.

Another object is to provide a fountain roller of the described character constructed so that the uniform distribution of ink applied to the type is substantially unaffected by the progressive diminution of the ink supply.

Another object is to provide a fountain roller of the described character which is mounted for convenient adjustment radially with respect to the cylinder or wheel carrying the type so that the contact pressure between the fountain roller and type may be varied.

A further object is to provide a fountain roller having the foregoing characteristics and capable of containing a relatively large supply of ink without unduly increasing the outer dimensions of the roller.

Finally, it is an object of the present invention to provide a fountain roller of the described character which is simple in construction and adapted for ease of assembly and maintenance.

In accordance with the invention, the above and other objects, features and advantages thereof are achieved by providing a fountain roller which includes upper and lower end plates formed with telescoping cylindrical parts. The cylindrical part extending from the upper end plate fits within the other cylindrical part with a relatively small clearance therebetween so that a capillary attraction will exist between ink in the annular space defined between the cylindrical parts and the confronting surfaces of the latter to cause such ink to rise in said annular space. Further, the cylindrical part depending from the upper end plate defines a central ink reservoir and terminates at its lower edge above the lower end plate so that ink may flow from the reservoir under said lower edge and into the annular space between the cylindrical parts. The cylindrical part extending upwardly from the lower end plate, that is, the outer cylindrical part, is formed with radial openings in the upper portion thereof to permit the ink to flow outwardly from the capillary space, and the outer surface of the outer cylindrical part is provided with one or more helical grooves extending downwardly from the radial openings to distribute the ink over that outer surface. The upper and lower end plates define radial shoulders at the opposite ends of the outer cylin-

2

drical part, and a felt or similar porous pad is wrapped around the outer cylindrical part between such shoulders to absorb the ink from the helical groove and to apply the ink to the type or marking elements. In order to

5 control the contact pressure between the felt pad on the fountain roller and the type or marking elements, mounting bosses extend from the opposite faces of the upper and lower end plates and rotatably receive eccentric pins which are rotatably adjustable on a suitable support for shifting the aixs of rotation of the fountain roller.

In order that a better understanding of the invention may be had, an illustrative embodiment thereof is hereinafter described in detail and illustrated in the accompanying drawings which form a part hereof, and wherein:

Fig. 1 is a side elevational view of a fountain roller embodying the present invention and shown in operative association with a marking cylinder or wheel which is adapted to carry type on the periphery thereof;

Fig. 2 is a vertical sectional view of the fountain roller of Fig. 1, but shown on an enlarged scale;

Fig. 3 is an elevational view of an element included in the fountain roller of Fig. 2;

Fig. 4 is an elevational view, partly broken away and in section, of another element included on the fountain roller of Fig. 2;

Fig. 5 is a detail view of an eccentric pin for rotatably supporting the fountain roller of Fig. 2; and

Fig. 6 is a detail view of another eccentric pin employed for rotatably supporting the fountain roller of Fig. 2.

Referring to the drawings in detail, a fountain roller embodying the present invention is there illustrated and generally identified by the reference numeral 10. The roller 10 is provided for applying ink to type or other marking elements carried on the periphery of a marking cylinder or wheel 12 which rotates about a vertical axis to mark the side surfaces of successive articles fed past the marking wheel. Accordingly, the roller 10 must rotate about an axis which is parallel to the axis of rotation of wheel 12 in order to make rolling contact with the type on the latter. However, when a fountain roller, that is, a roller containing a supply of ink, is rotated about a vertical axis, the ink applied to the type normally is unevenly distributed and there is a tendency for greater quantities of ink to be applied to the lower portions of the type. Further, in existing fountain rollers, the supply of ink to the type carried by the upper portions of marking wheel 12 is materially reduced, and even completely interrupted, when the level of ink within the roller is progressively lowered as the ink is consumed.

50 In accordance with the present invention, the above disadvantages of existing fountain rollers are avoided by forming the roller 10 of an upper end plate 14 and a lower end plate 16 which are respectively provided with cylindrical parts 18 and 20 extending axially therefrom.

55 The cylindrical part 18 is formed to telescope within the cylindrical part 20, as seen in Fig. 2, and the outer diameter of part 18 is only slightly smaller than the inner diameter of part 20 so that a thin annular space 22 is defined therebetween.

60 The outer cylindrical part 20 has an axial length which is greater than the axial length of the inner cylindrical part 18 so that the lower end edge of the latter is spaced from the lower end plate 16 when the outer cylindrical part abuts, at its upper edge, against the upper end plate 14. Thus, the central space 24 defined by the inside surface of inner cylindrical part 18 and forming an ink reservoir communicates with the annular space 22 under the lower edge of part 18.

65 The upper end plate 14 is formed with an opening 26 extending therethrough and communicating with the space 24 to permit the pouring of ink into the reservoir without requiring disassembly of the parts making up the

roiler and also to permit atmospheric pressure to act upon the surface of the ink in the space 24. The radial thickness of the annular space 22 is small enough to provide a capillary attraction between the ink entering that space from the reservoir 24 and the inner and outer surfaces of the cylindrical parts 20 and 18, respectively. Thus, the combined action of atmospheric pressure acting on the surface of the ink in space 24 and of the capillary attraction referred to above causes the ink in the annular space 22 to rise above the level of the ink in reservoir 24. In order to achieve the above mentioned capillary attraction, the radial thickness of the annular space 22 is preferably no greater than 0.03 of an inch.

The upper end plate 14 is preferably formed with a through bore which communicates with the upper end of the annular space 22 and is closed by a removable plug 27 so that the plug 27 may be removed to facilitate the escape of air from the space 22 during initial filling of the roller. The upper end plate 14 is formed with an axial rim 28 which extends above the upper surface of end plate 14 to prevent spilling over of the ink during filling of the reservoir 24, and also extends below the under surface of end plate 14 to encompass the upper portion of cylindrical part 20. An insert ring 30 (Fig. 2) is preferably secured within the depending portion of the rim 28, for example, by set screws 32, and the inner surface of the ring is screw threaded to engage meshing threads 34 formed on the upper portion of the outer surface of cylindrical part 20.

A tubular pad 36, formed of felt or other similar porous materials, fits around the cylindrical part 20 between the radial shoulders provided by the upper surface of end plate 16 and by the lower edges of rim 28 and ring 30, and preferably extends radially beyond these shoulders for rolling contact with type carried on the periphery of the marking wheel 12. In order to supply ink to the pad 36, radial openings 38 are formed through the upper portion of cylindrical part 20 and open into a circumferential groove 40 formed in the outer surface of the latter. Another circumferential groove 42 is formed in the lower portion of the outer surface of cylindrical part 20, and a helical groove 44 (Fig. 4) extends between the grooves 40 and 42. Thus, the ink rising in the annular space 22 flows outwardly through the openings 38 and is distributed vertically and circumferentially to the pad 36 by the grooves 40, 42 and 44.

In order to provide for the rotational mounting of the fountain roller in a manner permitting adjustment of the axis of rotation thereof relative to the axis of marking wheel 12 so that the contact pressure between the pad 36 and type on the marking wheel may be varied, the upper and lower end plates are formed with upwardly and downwardly extending central bosses 46 and 48, respectively. The bosses 46 and 48 are formed with axial blind bores 50 having suitable bearing bushings therein. The fountain roller 10 and the marking wheel 12 are preferably mounted on the same support arm 52 and the latter may be pivotally carried by a suitable support bracket 54 so that the wheel 12 may swing toward and away from the articles to be marked. The mounting of the fountain roller on support arm 52 is achieved by an axle 56 extending vertically through a bore (not shown) in the support arm. The axle 56 is formed with a reduced diameter central portion 58 (Fig. 5) to accommodate the end of a set screw 60 (Fig. 1) for locking the axle 56 in the support arm. The upper end of the axle 56 is formed with an eccentric portion 62 which extends into the bore 50 of lower boss 48. A lever 64 is formed with an opening adjacent one end which receives the lower end portion of the axle 56, and a set screw 66 is provided for preventing rotation of lever 64 relative to the axle. A connecting bar 68 extends upwardly from the free end of the lever 64 and at its upper end is secured to one end of another lever 70 extending parallel to the lever 64.

A stub shaft 72 extends downwardly from the lever 70 and is secured to the latter by a set screw 74. The shaft 75

72 has an eccentric lower portion 76 (Fig. 6) which extends into the bore 50 of the boss 46 so that the fountain roller 10 is rotatably mounted on the eccentric portions 62 and 76 of the axles 56 and 72, respectively. By loosening the set screw 60, and then swinging the connecting bar 68, the radial distance between the axes of rotation of the fountain roller and of the marking wheel may be conveniently adjusted. Further, since the rotatable mounting of the fountain roller is achieved by structure external of the reservoir 24, the capacity of the latter is not diminished by such structure and the maximum ink supply is made possible without unduly increasing the outer dimensions of the roller.

From the foregoing description of an illustrative embodiment of the invention, it is apparent that a fountain roller has been provided wherein the ink is fed to the pad 36 through the openings 38 adjacent the top portion of the pad and the grooves 40, 42 and 44 ensure the even distribution of the ink both circumferentially and axially. Further, as the level of ink in the reservoir 24 is lowered by the consumption thereof, the capillary attraction between the ink in space 22 and the wall surfaces defining that space ensures that the ink is raised sufficiently to reach to the openings 38. It should also be noted that the relatively large cross-sectional area of the reservoir 24 provides a relatively slow recession of the ink level in the reservoir as the ink is consumed so that the level of ink in the space 22 remains above the openings 38 for a relatively long operating period. The described structure has the additional characteristic of facilitating the separation of the cylindrical parts 18 and 20 and the removal of the pad 36 so that the parts may be conveniently cleaned to provide continuous and reliable operation of the fountain roller.

In the event that the capillary action obtained in the space 22 can be sacrificed along with the advantages of such capillary action, an inking roller embodying the present invention may be constructed without the cylindrical part 18. In a construction of this kind, the inking roller includes a cylindrical part 20 which is externally threaded at the upper end thereof, as at 34, and has a lower end plate 16, as shown in Fig. 4. An upper end plate 14 is also provided and has a peripheral flange 28 carrying an internally threaded ring 30 to removably engage over the threads 34. An absorbent pad 36 extends around the cylindrical part 20 between the end plates 14 and 16, and the cylindrical part 20 is formed with at least one radial opening 38 which communicates with an upper circumferential groove 40. A lower circumferential groove 42 is also formed in the outer surface of the cylindrical part 20, and a helical groove 44 extends downwardly from the groove 40 to the groove 42. As in the previously described embodiment, the upper end plate 14 is provided with an opening 26 to permit the pouring of ink into the chamber defined by the interior of the cylindrical part 20. So long as the level of the ink in the interior of part 20 is above the opening 38, ink flows outwardly through the latter into the grooves 40, 44 and 42 for even distribution to the pad 36. Thus, even in the absence of the cylindrical part 18, an inking roller constructed in accordance with this invention will produce a more uniform distribution of ink to the absorbent pad than has heretofore been possible with the existing devices.

While I have described and illustrated a particular embodiment of my invention, it is to be understood that the invention is not limited to the precise structure thereof, and that various changes and modifications may be made therein without departing from the spirit or scope of the invention.

What is claimed is:

1. An inking roller of the fountain type comprising vertical, concentric inner and outer cylindrical parts, said inner cylindrical part defining an ink reservoir, said inner and outer parts being spaced apart to provide an annular

space therebetween communicating at the bottom with said reservoir and the radial dimension of said annular space being sufficiently small to provide a capillary attraction between the ink in said annular space and the confronting surfaces of said cylindrical parts so that the ink in said annular space will rise above the level of the ink in said reservoir, an absorbent pad extending around said outer cylindrical part, and at least one opening extending radially through said outer cylindrical part so that ink may flow from said annular space through said openings for distribution to said pad.

2. An inking roller of the fountain type according to claim 1; wherein the outer surface of said outer cylindrical part is formed with an upper circumferential groove having said radial openings registering therewith, a lower circumferential groove, and a helical groove extending downwardly from said upper groove at least to said lower groove for effecting the axial and circumferential distribution of ink from said openings to said pad.

3. An inking roller of the fountain type comprising vertical, concentric inner and outer cylindrical parts defining a central ink reservoir and a narrow annular space between said parts, a lower end plate on the bottom of said outer cylindrical part, the lower end of said inner cylindrical part terminating above said lower end plate so that said central reservoir communicates with said annular space at the bottom of the latter, said annular space having a radial dimension which is sufficiently small to provide a capillary attraction between the ink in said annular space and the confronting surfaces of said inner and outer cylindrical parts so that the ink in said annular space will rise to a level above that of the ink in said reservoir, an absorbent pad extending around said outer cylindrical part, said outer cylindrical part having at least one opening formed in the upper portion thereof to permit ink to flow outwardly from said annular space, and the outer surface of said outer cylindrical part having groove means formed therein to effect axial and circumferential distribution of ink emitted from said openings to said pad.

4. An inking roller of the fountain type comprising upper and lower end plates, inner and outer telescoping cylindrical parts extending vertically from said upper and lower end plates, respectively, said inner cylindrical part defining a central ink reservoir and terminating above said lower end plate, said inner and outer cylindrical parts being spaced apart slightly to define a narrow annular space therebetween which communicates with said reservoir at the bottom under the lower edge of said inner cylindrical part, said annular space having a radial dimension which is sufficiently small to provide a capillary attraction between the ink therein and the confronting surfaces of said inner and outer cylindrical parts so that the ink in said annular space will rise to a level above that of the ink in said reservoir, threaded means for retaining said inner and outer cylindrical parts in telescoped relationship, an absorbent pad extending around said outer cylindrical part between said upper and lower end plates, said outer cylindrical part having radial openings extending through

the upper portion thereof so that ink may flow therethrough from said annular space, and groove means in the outer surface of said outer cylindrical part for axially and circumferentially distributing ink from said openings to said absorbent pad.

5. An inking roller of the fountain type according to claim 4; wherein said groove means includes an upper circumferential groove registering with said radial openings, a lower circumferential groove, and a helical groove extending from said upper groove downwardly at least to said lower groove.

6. An inking roller of the fountain type according to claim 4; wherein said upper end plate is formed with an opening extending therethrough and communicating with said reservoir so that the latter is vented thereby and ink may be supplied through said opening in the upper end plate to the reservoir without disassembling said inner and outer cylindrical parts.

7. An inking roller of the fountain type comprising a double-walled cylindrical body having end plates at the opposite ends thereof to define a central ink reservoir and an annular space within said double-walled body and extending around said reservoir, said annular space communicating at one end with said reservoir and having a

25 radial dimension which is sufficiently small to provide a capillary attraction between the ink in said space and the wall surfaces defining the latter so that ink in said annular space will rise to a level above that of the ink in said reservoir, the one of said end plates remote from said one end of the annular space having an opening extending therethrough and communicating with said reservoir to vent the latter to atmosphere and to permit the supplying of ink therethrough to said reservoir, an absorbent pad disposed around the outside of said double-walled body, 35 and means defining communicating passages in said body for communicating the portion of said annular space remote from said one end of the latter with said absorbent pad to permit ink to flow outwardly from said space into said pad.

8. An inking roller of the fountain type according to claim 7; wherein said one end plate has an additional opening extending therethrough and communicating with said annular space for venting said annular space to atmosphere during the filling of said reservoir and thereby to reduce 45 the resistance to the initial rise of ink in said annular space.
